CAP FOR USE WITH A LINK CHAIN SUPPORT POST

Michael T. Russo, Bloomfield Hills, Mich.
(1805 Larchwood St., Troy, Mich. 48084)

Filed May 20, 1974, Ser. No. 471,403

Term of patent 14 years

Int. Cl. D25—99

U.S. Cl. D28—1 C

FIG. 1

FIG. 2

FIG. 3

FIG. 4

FIG. 5

FIG. 6

FIG. 1 is a top plan view of a cap for use with a link chain post showing my new design.

FIG. 2 is a front and top perspective view thereof.

FIG. 3 is a front elevational view thereof, the rear elevational view being identical to the front.

FIG. 4 is a side elevational view thereof, the opposite side being identical.

FIG. 5 is a cross-sectional view taken on line 5—5 of FIG. 1.

FIG. 6 is a perspective view with the support posts being shown in broken lines for illustrative purposes only.

I claim:

The ornamental design for a cap for use with a link chain support post, as shown and described.
